UNITED STATES PATENT OFFICE.

HENRY J. HARDENBERGH, OF NEW YORK, N. Y., ASSIGNOR TO THE TUTTLE & BAILEY MANUFACTURING COMPANY, OF SAME PLACE.

DESIGN FOR A REGISTER-FRONT.

SPECIFICATION forming part of Design No. 23,934, dated January 1, 1895.

Application filed December 3, 1894. Serial No. 530,744. Term of patent 14 years.

To all whom it may concern:

Be it known that I, HENRY J. HARDENBERGH, a citizen of the United States, residing in the city and county of New York, in the State of New York, have invented a new and original Design for a Register-Front, of which the following is a specification, reference being had to the accompanying drawings.

- 10 Figure 1 is a face view. Fig. 2 is a cross section, and Fig. 3 a section of a portion on the line 3—3 in Fig. 1.

The leading feature of my design consists in the double cruciform ornament, within a narrow ring inclosed in a fret-work field, the whole surrounded by an open-work border.

In the center of the design is a small rosette A, surrounded by a diamond-shaped foliated ornament A', the angles of which are prolonged and branched to form four leaf-like ornaments A², A³.

A³, A³, are fern-like members based upon the sides of the diamond A', with two of their outwardly projecting scrolls joining the intermediate members A² on each side, while two further scrolls and a central stem are joined to the encircling ring B. This portion of the design is carved or molded in re-

lief, and is an adaptation of the Grecian honey-suckle decoration, with the members 30 disposed radially.

The ring and its contained ornament are inclosed by the frame B', and the field B², B³, composed of open-work waved lines, producing the effect of conventional scales.

35 C is a border consisting of a series of loops formed by the serpentine convolutions of a member C', touching the frame B', and the plane outer margin D at the bights of the several loops, and ornamented at these points 40 by hemispherical beads C².

The border C and the fields B², B³, are sunk slightly to present the remaining members more prominently to the eye, while the upper surface of the convoluted member C' is 45 brought to a sharp edge to render the border still less conspicuous, and to further accentuate that portion of the design within the ring.

I claim—

50 The design for a register front substantially as shown.

II. J. HARDENBERGH.
